UNITED STATES PATENT OFFICE.

WILEY JONES, OF WESTERLY, WEST VIRGINIA.

SPEEDER MECHANISM FOR MOTOR-BOATS.

1,239,186.

Specification of Letters Patent.

Patented Sept. 4, 1917.

Application filed February 12, 1917. Serial No. 148,069.

To all whom it may concern:

Be it known that I, WILEY JONES, a citizen of the United States, and resident of Westerly, in the county of Fayette and State of 5 West Virginia, have invented certain new and useful Improvements in Speeder Mechanism for Motor-Boats, of which the following is a specification.

This invention relates to marine propulsion, and more specifically to a speeder mechanism for motor boats.

The object of my invention is to provide a mechanism whereby the propulsive power will be directed to the prow of a boat both 15 forwardly and upwardly, instead of against the engine in the rear of a boat as motor boats are at present constructed. The forward force of the propulsive power as directed to the prow of the boat by my mechanism removes all forward pressure from the 20 engine, thus making the engine run more freely and easily due to lessened frictional engagement; it also greatly lessens the wear and tear on the engine. The upward force 25 of the propulsive power tends to raise the prow of the boat from the water, thus lessening frictional engagement in its progress and greatly increasing the speed of the craft in proportion to the energy utilized.

30 Other objects of this invention not at this time more particularly enumerated, will be clearly understood from the detailed description and drawings forming a part of this specification.

35 Furthermore, this invention consists in the novel arrangement and combination of parts more particularly described in the following specification and embodied in the claims appended hereunto and forming a part of 40 this application.

Referring now to the drawings, which are merely illustrative of my invention;

Figure 1 is a longitudinal sectional view through a boat equipped with my speeder 45 mechanism;

Fig. 2 is a horizontal sectional view of the same taken on the line 2—2 of Fig. 1;

Fig. 3 is a detail top plan view of my sliding universal joint;

50 Fig. 4 is a side elevation of the same.

Referring further to the drawings, wherein similar reference characters designate similar parts throughout the respective views, 1 designates the hull of a boat while 2 55 is an engine mounted therein, said engine be-

ing provided with the customary main shaft 3 and fly-wheel 4. Upon the rearward end of said main shaft 3 is mounted a sliding universal joint 5. Said sliding universal joint is constructed of a metal piece centrally disposed with respect to bifurcated members 6 fixed to both ends thereof, each prong of said bifurcated members being provided with a slot parallel to a similar slot in the opposite prong. A sliding pin 8 is 60 secured transversely through the end of the main shaft 3, said pin being adapted to have a reciprocating movement within the slots 7 of one of the bifurcated ends of joint 5, while a sliding pin 9 is secured transversely 65 near the inner end of the propeller shaft 10 and is adapted to have a reciprocating movement within the slots 7 of the opposite bifurcated end of joint 5. The outer or rearward end of the propeller shaft 10 has 70 mounted thereon a propeller 11. A collar 13 is adjustably mounted by means of a set screw 14 upon the propeller shaft 10. Forward of said collar 13 and surrounding the shaft 10 is an oil boxing 12, wherein said 75 shaft may revolve freely and may also have a reciprocating movement. Integral with the transverse sides of said oil boxing 12 are fixed oppositely extending arms 15 whose ends project through upright guide members 80 85 16 mounted upon the floor of the boat. A clevis 17 is fixed to the free end of each arm. Speed bars 18 are mounted to said clevises by means of rigid joints 19. The said speed bars may be bent to conform to the shape of 90 any particular boat to which my mechanism is fitted, though the usual construction is to have them extend outwardly and forwardly a certain distance, thence forwardly and upwardly on both sides of the boat to a point 95 near the top of the prow thereof, where the ends of the said speed bars are secured at 20.

In revolving the propeller for movement of the boat forward, the propeller shaft being slidably mounted upon the sliding universal joint 5, which in turn is slidably mounted upon main shaft 3, the said propeller shaft is caused to move forward within oil boxing 12. Such forward movement of the propeller shaft is arrested when the 100 collar 13 contacts with the oil boxing, which also serves as a bearing for transmitting the forward pressure of the propeller to the arms 15, thence to the speed bars 18 which, by reason of their shape and the point of the 105 110 115

boat where the ends are secured, receive a pressure both forward and upward at the prow of the boat.

The utility, adaptability, and advantages 5 of my improved form of speeder mechanism for motor boats being obviously apparent, it is unnecessary to further enlarge upon the same herein.

Having now described and pointed out the 10 new and useful features of my invention, I do not limit myself to the shape of certain parts where the shape is not essential, nor do I restrict myself to the exact details of construction shown and described, but mean 15 and intend to claim all equivalents and variations thereof not departing in principle from my invention and falling within the purview of the appended claims.

What I claim as my invention and desire 20 to secure by Letters Patent is:

1. In a device of the kind described, the combination of a boat, an engine mounted in said boat adapted to revolve a propeller shaft, means interposed between said propeller shaft and the main shaft of said engine whereby said propeller shaft may have 25 horizontal reciprocating movement, cross-arms slidably mounted upon said propeller

shaft, a collar adjustably mounted upon said propeller shaft rearwardly of said cross-arms, and forwardly and upwardly extending speed bars mounted at one end to the ends of said arms and at the other end to the 30 prow of the boat.

2. In a speeder mechanism for motor boats, the combination of a boat, an engine 35 mounted in said boat, a main-shaft adapted to be rotated by said engine, a propeller shaft, a coupling connecting said main-shaft and said propeller shaft whereby they may be rotated at an angle to each other, means 40 forming a part of said shafts and said coupling whereby said propeller shaft may have reciprocating movement forwardly and backwardly, means adjustably mounted on 45 said propeller shaft whereby said reciprocating movement forwardly may be regulated, cross-arms slidably mounted about said propeller shaft forwardly of said last-named means, means connected to said cross-arms and to the prow of a boat whereby forward propulsive force will be directed to the 50 prow of the boat.

In testimony whereof, I affix my signature hereto.

WILEY JONES.
